UNITED STATES PATENT OFFICE.

LOUIS WOJIDKOW, OF BROOKLYN, NEW YORK.

DESIGN FOR A STAND FOR CHAFING-DISHES.

SPECIFICATION forming part of Design No. 26,484, dated December 22, 1896.

Application filed November 13, 1896. Serial No. 612,034. Term of patent 3¹ years.

To all whom it may concern:

Be it known that I, LOUIS WOJIDKOW, a citizen of the United States, residing in Brooklyn, county of Kings, and State of New York, have invented and produced a new and original Design for Stands for Chafing-Dishes, of which the following is a specification, reference being had to the accompanying drawing, which shows the same in perspective.

10 The leading feature of my design consists of an upper beaded ring and a lower ring having a series of hollows or depressions therein, standards having their upper portions fluted and lower portions plain, and ornamented 15 brackets connecting said lower ring with said standards.

A represents the upper ring, beaded on its outer edge, and B the lower ring, having the depressions *b* therein.

C represents the standards, fluted at their 20 upper ends, as at *c*, and plain at their lower ends, as at *d*, terminating in the feet *e*.

D represents the arms or brackets, curved as shown and connecting said lower ring B with the standards C. 25

What I claim is—

The design for a stand for chafing-dishes, as herein shown and described.

LOUIS WOJIDKOW.
